CLAIM

The ornamental design for jaw for surgical instrument, as shown and described.

DESCRIPTION

1. Jaw for surgical instrument

1.1 : Perspective

1.2 : Front

1.3 : Back

1.4 : Left

1.5 : Right

1.6 : Top

1.7 : Bottom

The dashed broken lines in the drawings show portions of the jaw for surgical instrument that form no part of the claimed design. The dot-dash broken lines in the drawings show boundaries that form no part of the claimed design.

1 Claim, 7 Drawing Sheets(56)
